Primary Examiner — Susan E Krakower*Assistant Examiner* — Christina M. Dodson*(74) Attorney, Agent, or Firm* — BakerHostetler(57) **CLAIM**

The ornamental design for a lamp, as shown and described.

DESCRIPTION

FIG. 1 is a perspective view of the lamp showing the new design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken lines in the figures show portions of the lamp that form no part of the claimed design.
